FRANK W. MERRICK, OF DORCHESTER, MASSACHUSETTS, ASSIGNOR TO WONDER
WEAVE, INC., OF BOSTON, MASSACHUSETTS, A CORPORATION OF MASSACHUSETTS

THREAD TENSION

Application filed February 24, 1930. Serial No. 430,715.

This invention relates to let-off means for thread and similar wound material and it has for its object to provide a let-off means which shall be simple in construction, of such compact form as to adapt it for use in shuttles or shuttle-like devices, and which, while capable of being set or adjusted at will to change the tension on the thread, will preserve the tension equable at all times. The invention 5 relates particularly to that class of let-off means in which the thread or equivalent is supplied by a revoluble wound package thereof which rotates under draft on the thread and subject to the braking resistance of a 10 lever against which the thread bears at a guiding point removed from its fulcrum in a way when tautened to shift the lever from the package. According to this invention the lever is so constructed, and also so arranged 15 with respect to the package, that a straight line connecting the fulcrum and thread-guiding points of the lever crosses the wound mass of the package intervening between said points, so that with the thread tautened it 20 extends from the wound mass of the package to the said guiding point of the lever in a rearwardly directed tangent; therefore a rearwardly extending bend or bight (constituting an important factor in the main) 25 will be formed in the thread at said guiding point on draft being exerted on the thread in the direction most favorable to movement 30 of the lever by the thread, or forwardly. In the example herein shown the lever extends around the forward side of the package, and that is material in that thereby the lever may be made very light but strong and that it 35 leads to compactness of construction and contributes to house the windings of the package. In the preferred construction the braking point of the lever is relatively near its fulcrum, so that the lever is very sensitive to 40 the displacing influence of the thread. In the example the package comprises, with the wound mass of thread, a core therefor, and it is against this rather than said mass that the lever has braking contact; but this is not 45 50 indispensable.

In the drawing, Fig. 1 is a plan of a thread-supply device or carrier here embodying my invention and of its holding means; Fig. 2 is a section on line 2—2, Fig. 1; Fig. 3 is a section on line 3—3, Fig. 1; and Figs. 4 and 5 are front and side elevations of what is shown in Fig. 1. The body 1 of the thread-supply device or carrier tapers in plan at both ends, after the 60 manner of an ordinary shuttle, and at one end it is beveled at the top and at the other at the bottom. It is held stationary by two pairs of jaws 2 whose members in each pair are intergeared in any way, as at 3, so that 65 they move into and out of gripping relation to the carrier together. A spring 4 acting on a member 5 bridging the two lower jaws tends to keep the two pairs of jaws open or out of gripping relation, but means (not 70 shown) acting on push-rods 6 so as to close the jaws alternately keeps the carrier always held by one or the other pair. Thus, as in my said application, filling may be passed through sheds formed in the warp B 75 (Fig. 1) over the carrier from the right of the fabric-and-warp sheet A—B and back under the carrier in loops which will be caught by the thread C extending from the carrier and which thus binds in these loops 80 as filling components of the fabric A, thread C thus becoming an edge warp. This thread C should in such a case as this be under a tension which is variable at will but equable in all possible conditions under which the 85 weaving may be carried on, thus to insure uniformity of the edge of the fabric in which it lies.

Thread C extends from a mass C' thereof wound on a bobbin or core 7, they forming 90 a wound package which is revoluble on a stud 8 upstanding from an open-top recess 9 formed in the body 1 and which at the back conforms to the (circular) shape of the bobbin but at the front is open, as shown at 1a; 95 communicating with this recess is a forwardly open undercut 10 having a fulcrum pin 11 fixed in its top and bottom walls (Fig. 2). The body 1 stands with the open-top 100 of its recess up, and when the package is

placed in the recess it operatively reposes therein due to gravity alone; it is readily removable by inverting the carrier. On pin 11 is fulcrumed the brake lever or tension lever 12, which here extends around the periphery of the package so that a flat 13 affording the braking point of the lever and an eye 14 affording the thread-guiding point thereof are in a straight line which crosses the wound mass C of the package when the lever is subject to the pressure of a plate-spring 15 which is attached to the fulcrum end of the lever and bears against and is subject to adjustment by a set-screw 16 tapped into the carrier body. In this example the flat 13 of the lever contacts with the peripheral flanges of the bobbin of the package, as shown in Fig. 3.

I am aware, as indicated, that left-off means have been proposed in which a brake lever is normally held against the wound mass and has a guide for the thread by which the latter when tautened tends to displace the lever from the package; but so far as I am aware this is the first instance in which the thread guiding and fulcrum points of the lever have been so related to the wound mass of the package that a straight line connecting them crosses the package, with the result that the thread assumes a rearward tangent to said mass and the mentioned advantage consequent thereon follows.

Having thus fully described my invention what I claim is:

1. In combination, supporting means, a wound package journaled thereon, and a brake lever yieldingly held in braking contact with a peripheral surface of the package and having a guide for the wound material extending from the wound mass of the package, the fulcrum and guide of the lever being arranged in a straight line crossing said wound mass.

2. In combination, supporting means, a wound package journaled thereon and including a core and a wound mass thereon, and a brake lever yieldingly held in braking contact with a peripheral surface of the core and having a guide for the wound material extending from said wound mass, the fulcrum and guide of the lever being arranged in a straight line crossing said wound mass.

3. In combination, supporting means, a wound package journaled thereon, and a brake lever yieldingly held in braking contact with a peripheral surface of the package and having a guide for the wound material extending from the wound mass of the package, the fulcrum and guide of the lever being arranged in a straight line crossing said wound mass, the point of braking contact of the lever with the package being near said fulcrum.

4. In combination, supporting means, a wound package journaled thereon, and a

brake lever yieldingly held in braking contact with a peripheral surface of the package and having a guide for the wound material extending from the wound mass of the package, the lever extending around the periphery of said wound mass at that side of the package from which the material extends from the mass to said guide and having its fulcrum and the guide arranged in a straight line crossing said wound mass.

5. In combination, a carrier body having a recess therein, a wound package journaled on said body, said recess having an opening opposite the periphery of the package at one side of a diameter thereof, a brake lever in said opening arranged at said side of said diameter and fulcrumed in said body and having a guide for the wound material extending from the package and one of its end portions reaching between the periphery of the package and a surface of the opening, and a spring interposed between said end portion and surface and holding the lever in braking contact with the package.

6. In combination, a carrier body having a recess therein, a wound package journaled on said body, said recess having an opening opposite the periphery of the package at one side of a diameter thereof, a brake lever in said opening arranged at said side of said diameter and having one of its end portions reaching and fulcrumed in said body between the periphery of the package and a surface of the opening and also having a guide for the wound material extending from the package, and a spring interposed between said end portion and surface and holding the lever in braking contact with the package.

7. In combination, a carrier body having a recess therein, a wound package journaled on said body, said recess having an opening opposite the periphery of the package at one side of a diameter thereof, and a brake lever arranged in said opening at said side of said diameter and fulcrumed in said body near said diameter at one side of the package and having a guide for the wound material extending from the package arranged near said diameter at the opposite side of the package and normally held in braking contact with the package.

In testimony whereof I affix my signature.

FRANK W. MERRICK.
